UNITED STATES PATENT OFFICE.

NEWTON ROGERS AND JAMES A. WHARRY, OF TERRE HAUTE, INDIANA.

GAS-ENGINE.

SPECIFICATION forming part of Letters Patent No. 403,379, dated May 14, 1889.

Application filed August 22, 1888. Serial No. 283,451. (No model.)

To all whom it may concern:

Be it known that we, NEWTON ROGERS and JAMES A. WHARRY, of Terre Haute, in the county of Vigo and State of Indiana, have invented certain new and useful Improvements in Gas-Engines; and we do hereby declare that the following is a full, clear, and exact description of the invention, which will enable others skilled in the art to which it appertains to make and use the same, reference being had to the accompanying drawings, and to the letters of reference marked thereon, which form part of this specification.

Our invention relates to an improvement in gas-engines, and has for its object to produce a two-cylinder engine, the connecting-rods of which operate one crank-pin, the valves of the two cylinders being operated from a single way-shaft, and the speed of the engine being controlled by mechanism which will exert its influence upon each cylinder in a manner so as to throw one of them out of operation in advance of the other on attaining a speed above the normal. The explosive mixture used in the cylinders may be any fuel-gas and air; but I preferably use a carburetor and manufacture the carbureted air on the spot. The ignition is effected by means of an electric spark produced by a "dynamo" operated by the engine. By means of the mechanism hereinafter described the engine may be operated with a single cylinder, if desired. I accomplish these objects by means of the mechanism illustrated in the accompanying drawings, in which—

Figure 1 is an elevation showing one part in vertical section. Fig. 2 is a plan. Fig. 3 is an end elevation. Fig. 4 is a sectional detail of the way-shaft and governor connections. Fig. 5 is a sectional detail showing the manner of connecting the main and way shaft.

Similar letters of reference indicate like parts in all the views.

A represents the frame of the engine, and B the two cylinders bolted thereon. Each cylinder is provided with a combustion-chamber, C, which is not entered by the piston.

D is the piston, and E represents connecting-rods from the two pistons to the single crank-pin F. The crank-pin F is keyed or otherwise secured in the disk-crank G on the

main shaft H. Each cylinder is provided with a head, I, suitably cored for the circulation of water which enters at J and passes out of the jacket K at L. The cylinder is provided with cooling-ribs M, which radiate the surplus heat to the water and afford a large area of cooling-surface. Each cylinder is provided with pipe-connections and a main valve, N, thereon for the admission of the gaseous mixture. The valve N is fed with carbureted air or with gas through a check-valve, O, and stop-valve, P by a pipe, Q, leading from the carburetor R, and with air by means of a stop-valve, S. The two stop-valves serve to regulate the strength of the mixture, and the check-valve to prevent the return of any gas or flame to the carburetor which may leak past the main valve during compression and ignition. The main valves are operated in a manner to be hereinafter described, and the mixture passes from thence by port T to the cylinder during the suction-stroke and is compressed in the combustion-space C during the return-stroke of the piston.

Each cylinder is provided with an exhaust-valve, U, operated as described hereinafter, and the exhaust from each cylinder passes into casing a, surrounding the air-inlet pipe b of the carburetor, by means of pipes c, and heats the air to be carbureted, and finally leaves the casing by pipe d.

As the carburetor is made the subject-matter of a separate application filed August 22, 1888, Serial No. 283,449, it will not be described here in detail. The main shaft is supported in bearings H' H'', fixed to the main frame A, and is provided with a worm, A', keyed thereon. This worm gears with a worm-wheel, A'', secured to a way-shaft, A³, by means of pins or bolts g, as shown more fully in Fig. 7. This way-shaft extends the full length of the engine and is mounted in revolving bearings B', which revolve in bearings B'', fixed in brackets B³, secured to the cylinder.

The connection between the way-shaft and the bearings B' is formed by pins or bolts h. This way-shaft is therefore revolved by the main shaft without longitudinal play or movement. On the main engine-shaft is mounted a centrifugal governor, C', which slides a collar, C², back and forth upon the shaft as the balls of the governor fly out or are retracted.

As the collar C³ moves, it communicates its motion to a double-forked bell-crank, C⁴, to a roller, D', which is rigidly secured to a sleeve, D², which slides upon the way-shaft A². Slots 5 g' and h' permit this movement by the bolts g and h, respectively. To the revolving bearings B are attached caps D³, which contain stiff springs E², which are caused to bear against the ends of the sleeve D² and are adjusted by means of bolts and jam-nuts i, j.

The resistance to the centrifugal force of the governor-balls is thus adjusted according to the compression of these springs, and the springs E² cause the sleeve D² to return to its 15 normal position as the speed becomes normal.

Upon the way-shaft A² are rigidly secured two exhaust-cams, G', facing in opposite directions to suit the operation of the two cylinders, respectively. On the sleeve D² are 20 secured the two inlet-valve cams G³, which are provided with a series of steps, 1 2 3, as shown, if desired, or only a single cam-surface can be used on each cam, according as the engine is to be controlled by gradually reducing the inlet-opening before finally keeping it closed altogether as the speed increases or as the cut-off is to be secured at once on an increase of speed beyond the normal. The 25 exhaust-cam operates the levers G³ to open the exhaust-valves alternately.

The inlet-cams operate the inlet-valves N through the medium of levers I'. These levers are provided with friction-rollers to roll upon the surface of the cams. The inlet and 30 exhaust valves are provided with springs, which keep the valve closed unless opened by the levers, as shown.

The caps D³ are provided with cams pointing in opposite directions, for operating the 35 ignitor-rod I², which is provided with a retracting-spring, I³, and adjusting-screw J'. The rods I² operate rock shafts K', connected with the curved electrode K², which makes and breaks contact with a fixed electrode, K³.

45 The engine-shaft is provided with a pulley, L', fixed to the shaft for transferring the power to driven machinery, with the pulley L² running loosely upon the shaft, but turned thereby through connection with a spring-held pawl, as more specifically described in our application filed August 22, 1888, Serial 50 No. 283,448, for operating the dynamo M', and a fly-wheel, M², keyed to the shaft, to provide the necessary means for storing momentum 55 and conducting the even movement of the engine.

The dynamo M' is provided with a wide-belt-pulley, M³, and belt N², connecting it with belt-pulley L². An idle-wheel, N³, can be 60 thrown into and out of gear with the fly-wheel and the dynamo-pulley, as described in our said application, Serial No. 283,448.

65 The warm-air-inlet pipe to the carburetor is provided with a valve, O', by means of which cold air may be admitted to the warm air to regulate the temperature of the carburetor and the gases evolved therein, as more

fully set forth in our ~~said~~ application for carburetor filed August 22, 1888, Serial No. 283,449.

70 The operation of engine is as follows: The engine being turned by hand, on the outstroke of each piston in succession a charge of carbureted air, of regulated strength and temperature, and a charge of atmospheric air are drawn by suction through valves P, Q, S, and N into the cylinders. On the return-stroke of each piston the charges are compressed into the combustion-chambers and then fired by the electric spark produced by 80 the igniting apparatus, as explained in our application filed August 22, 1888, Serial No. 283,452. Thus while one engine is drawing its charge the other is compressing its charge, and then fires it while the first engine compresses. The second engine then exhausts 85 while the first is making its power-stroke, then to exhaust in its turn. The exhaust products serve to heat the carburetor, as already described, before reaching the atmosphere. The regulation of the speed is effected as described in our application, Serial No. 283,450—that is, each cam is moved to the left as the speed increases, and the inlet-valve lever drops from one cam-step to the other, 90 thus decreasing the lift of the inlet-valve; or if only one cam-surface is used instead of the steps the gas-inlet valve will at once fail to open. The two cams occupy such a relative position with respect to the inlet-valves that 95 the right-hand engine drops off the cam sooner than the left-hand engine, thus throwing it idle when excessive speed takes place, and at a still higher speed both engines run idle. Although we have here described a compression engine as the most desirable one for utilizing explosive gases, it is evident that by having the worm and worm-wheel of the same size, instead of the wheel being twice the size of the worm, we would have a simple non-compression engine. The engine could also be 100 changed to a different cycle by changing the relative diameters of worm and wheel to suit.

105 It will be seen that for light running one of the engines may be disconnected altogether, and the additional bearing-piece slipped in under the crank-pin rings, thus avoiding the friction which would ensue on account of running the second engine idle constantly, and also avoiding the danger of "miss fires" owing 110 to running two engines with very light charges, which charges, on account of their smallness, might be injuriously mixed with too large a quantity of the waste gases not cleared by the exhaust.

115 We do not in this application claim the ignitor, the governing apparatus, the carburetor, or the dynamo-operating mechanism separately, as we have already claimed them in separate applications, as mentioned above; 120 but

125 What we do claim as new, and desire to secure by Letters Patent, is—

1. The combination, with a gas-engine, a

- main shaft thereof, a worm thereon, a wheel gearing with said worm rigidly secured to a way-shaft, an exhaust-cam on said way-shaft, and a sleeve adapted to move longitudinally 5 on and revolve with the way-shaft, of an inlet-valve cam on said sleeve and revolving bearings in which the ends of the way-shaft are secured and in which the sleeves move longitudinally, and means for shifting the sleeve 10 longitudinally in the bearings and on the way-shaft upon a change of speed of said engine, substantially as described.
2. In a gas-engine, the combination of a way-shaft operated from the main shaft, revolving bearings in which the ends of the way-shaft are secured, a sliding sleeve on said way-shaft and in said revolving bearings, an exhaust-valve cam on the way-shaft, inlet-cam on the sleeve, a cap secured to the end 15 of the revolving bearings, and an ignitor-cam on said cap, substantially as described.
3. In a duplex gas-engine, the combination, with a main shaft, a way-shaft operated thereby, revolving bearings in which the ends of the way-shaft are secured, a sleeve sliding on said way-shaft and in said revolving bearings, exhaust-cams on the way-shaft, inlet-cams on the sleeve, caps secured to said bearings containing springs bearing on the ends 20 of the sleeve, ignitor-cams on said caps, and connections with a governor for sliding said sleeve independently of the way-shaft, whereby the positions of the inlet-cams may be altered without altering the positions of the exhaust-cams, substantially as described.
4. In combination with the way-shaft of a gas-engine operated by worm-gear connection with the main shaft thereof, a governor on the main shaft and connections therefrom 25 to a sliding sleeve on the way-shaft, revolving bearings carried by brackets secured to the ends of the way-shaft in which said sleeve slides, connections between the way-shaft and the sleeve for causing them to revolve together, springs for keeping the sleeve in a 30 normal position longitudinally on the way-shaft and to resist the action of the governor, means for adjusting the compression of said springs, inlet-cams on the sleeve, ignitor-cams 35 attached to the revolving bearings, and exhaust-cams on the way-shaft, substantially as described.
5. In combination with the two gas-engines, connections therewith and with a single 40 crank-pin and crank-shaft, a way-shaft operated by this shaft, two exhaust-cams on the way-shaft, a sleeve on the way-shaft, two inlet-cams on this sleeve, the distance between them being less than the distance between 45 the respective inlet-valve levers operated by

said cams, means for shifting the sleeve lengthwise as the speed of the engine varies, whereby the inlet-valve of one engine is rendered inoperative in advance of the other, and revolving bearings and caps secured to the 5 way-shaft in which the sleeve slides having ignitor-cams thereon and operating a reciprocating electric ignitor, substantially as set forth.

6. A gas-engine cylinder provided with heat-radiating surfaces surrounded by a water-jacket, whereby the cooling contact with the air-circulating water is increased, substantially as described.

7. In combination with the two cylinders of a duplex gas-engine, inlet-valves therefor, connections between said valves and a carburetor, exhaust-valves connected with the cylinders and connections therewith and with a jacket surrounding the air suction-pipe of the carburetor, a common outlet from said jacket, and a cold-air valve in said suction-pipe for varying the temperature of the heated air of the carburetor and controlling the temperature of the charge admitted to the cylinders, and air-valves connected with the engine-inlet, substantially as described.

8. The combination, with the main shaft H of a gas-engine, of a worm, A', thereon, a worm-wheel, A², gearing therewith, secured by pins 90 g to a way-shaft, A³, a sleeve, D², sliding on the shaft A³, and slots g', to permit this sliding by the pins g, said pins causing the shaft A³ and sleeve D² to revolve together, said sleeve and way-shaft serving to carry the inlet and ignitor cams and the exhaust-cams, respectively, substantially as described.

9. In combination with a duplex gas-engine, a way-shaft and governor operated thereby, a sliding sleeve on the way-shaft operated by said governor, inlet-cams on the sleeve, exhaust-cams on the way-shaft, revolving bearings for keeping the way-shaft in a fixed longitudinal position, ignitor-cams attached to said bearings, adjustable electric 100 igniting devices operated by said cams, and a carburetor heated by the waste heat of the engine for supplying the gas to the inlet-valves, and connections from the exhaust-valves of the cylinders to a heater for the 105 air-inlet of the carburetor, substantially as described.

In testimony that we claim the foregoing as our own we affix our signatures in presence of two witnesses.

NEWTON ROGERS.
JAMES A. WHARRY.
